CLAIM

The ornamental design for oil filler, substantially as
shown and described.

DESCRIPTION

FIG. 1 is a perspective view of an oil filler showing my
new design;

FIG. 2 is a front elevational view thereof, the rear being
identical in appearance;

FIG. 3 is a side elevational view thereof, the opposite
side being identical in appearance;

FIG. 4 is a top plan view thereof; and

FIG. 5 is a bottom plan view thereof.
